UNITED STATES PATENT OFFICE

EDWARD C. ANGELL, OF NEW YORK, N. Y.

APPARATUS FOR SEALING CONTAINERS

Application filed March 20, 1926, Serial No. 96,128. Renewed January 26, 1929.

This invention relates to apparatus that will automatically fill containers as fed along a conveyer, with liquid or other material, and which containers as advanced will have the 5 open top closed and sealed by suitable means, such as an applied securing member.

One of the objects of the invention is to provide improved means for sealing a container that is made of flexible material, such 10 as paper, wherein the circular open mouth or top is pressed together from opposite sides, as by jaws, and thus it is collapsed, and the sealing lips thus formed, are secured by suitable means.

15 A further object of the invention is to provide means for feeding securing members, such as angular strips of metal, across onto the closed lips of the collapsed container, and thereupon pressing together the sides of the 20 angle strip to securely close and hold the meeting lips of the container.

Another object of the invention is to provide in addition to the collapsing and strip securing means, means for further securing 25 the angle strip in position.

In the accompanying drawings showing embodiments of my invention

Fig. 1 is a plan view partly in section.

Fig. 2 is a front elevation.

30 Fig. 3 is an end view, partly in section.

Fig. 4 is a cross section enlarged indicated on the line 4-4 of Fig. 2.

Fig. 5 is a partial view enlarged showing the collapsing means.

35 Fig. 6 is a detail of the latter.

Fig. 7 shows one of the filling devices.

Fig. 8 shows enlarged part of the closure means.

Fig. 9 is a detail of the strip feeding means.

40 Fig. 10 shows the advanced closure means.

Fig. 11 shows the upper part of a sealed container.

Fig. 12 shows one of the blocks on the conveyer that receives the container.

45 Fig. 13 is a side view of the latter.

Fig. 14 shows the strips for closing the container.

Fig. 15 shows the spring clip on the block.

50 Figs. 16 and 17 show the closing slides or jaws with the yielding jaws.

As shown in the drawings my invention comprises a base or table 1 mounted on suitable legs 2. At one end of the apparatus is located a filling tank 3, on standards 4, 5. This is of elongated form and at the front is 55 provided with a series of extension chambers 6, twelve of which are shown arranged in a line, see Figs. 1-3. Each of these chambers is provided with a suitable liquid delivering means operated from a main driving shaft 60 to each deliver the same predetermined quantity of liquid from the tank 3, that may be milk or any desired material.

These twelve filling devices are designed to 65 cooperate with twelve containers carried by an endless belt or chain 27, extending the length of the machine and carried around sprockets 28 and 29. The latter is advanced intermittently whereby to move the container holders 30 on the chain a unit distance. The 70 holders 30, see Fig. 12, carried by the chain 27, are provided with angular clips 31 and 32, the latter each having a slot at its angular connection with the base, will be slightly yielding, and this upward bend will engage 75 with the bead on the bottom of the container. At the rear stops 33 may be provided, a container being slid across the holders from the front until it strikes these stops by which it will be properly positioned on the holder. 80

The rear sprocket 29 is mounted on a cross shaft 34, see Fig. 1, actuated by a ratchet wheel 35 thereon engaged by a pawl 36. The latter is carried by an arm 37 rocked from a cam 38 on a cross shaft 39. This shaft is 85 turned by a gear 40 thereon engaging a gear 41 on the main shaft. A spring bolt 42 slides in a bracket 43 and operated by a cam 44 on shaft 39. This bolt engages a notched disk 45 on the cross shaft 34 after the pawl 36 90 has advanced this shaft the proper distance, so that the sprocket 29 will advance the conveyer chain the distance of one holder, and serve to lock the chain at each step.

The containers A, see Fig. 8, are preferably 95 of stiff paper of a somewhat frusto-conical shape with the upper end open and of circular form. It is desired to close the container by simply collapsing the upper end, usually done by jaws from opposite sides that 100

will bring the sides together, as indicated in Fig. 10. This is done and thereupon suitable sealing means is applied to secure the opposite sides brought together. This is preferably done by a strip of channel arrangement, as indicated in Fig. 14. These strips are nested together as shown in this view by being superposed, and placed in a suitable hopper 46, see Fig. 9. This hopper, and also the closing and applying means are mounted on a suitable carrier 47, see Fig. 6, having bosses 48 by which it is secured to four posts 49. The latter slide vertically in guides 50 at the base, and guides 51 on the table 2. A cross shaft 52 is suitably mounted below the table, with a rock arm 53 on one end that is rocked from a bar 54 operated by a groove cam 55 on the main shaft 12, and the latter is so designed that the carrier 47 is held in the upper position for a certain interval then lowered and held in the lower position for a certain interval. During the later the chain advances one unit, then the holder is brought down, then operated and then retracted for the next container to be advanced.

On the holder 47 are slides 56 and 57 having jaw ends 58 and 59. These each carry a pivoted jaw 60, 61, that are pressed toward each other by springs 70 and 71, see Fig. 16. Cams 62 and 63 on the shaft 12 operate levers 64 and 65, with forked ends that engage pins 66 and 67 on the slides 56 and 57. A spring 68 connects these levers tending to separate the jaws.

It will be seen from Figs. 8 and 10 that when the container A is brought beneath the jaw members, and the latter lowered by the described mechanism the jaws 58 and 59 are moved inwardly from the positions indicated in broken lines in Fig. 8. The extending jaws 60, 61, will engage the container on opposite sides and collapse it as indicated in this view. These cams are so designed that at this stage, the jaws will rest in this position, and the hinge jaws will press the lips together below the top edge of the meeting ends. At this time a slide 104 connected with the hopper 46, is operated by cam arm 102, engaging a cam 101 on shaft 12, see Fig. 4. This will serve to advance the lowermost angle strip, B, across the top of the collapsed container, see Fig. 9, and it will feed above the swinging jaws 60 and 61, see Fig. 8. At this stage the jaws 58 and 59 are further advanced and the swinging jaws 60 and 61, engaging opposite sides of the collapsed containers swing since they cannot advance, and must swing outwardly on their pivots, and bring the side faces of the jaws opposite their pivots against the angular strip, and close it tightly against the container lips. When the jaws 58 and 59 retreat, the spring jaws will move back to their former position.

65 The carrier for these jaws is now raised,

and the conveyer will advance the sealed container, which is done step by step until it reaches the station at the securing jaws. Here a pair of jaws 83 and 84 slide in a carrier 80 that moves vertically on posts 81, through a crank arm 82 on the cross shaft 52. This carrier is lowered at the same time the described carrier is lowered, and the jaws 83 and 84 are brought together to engage the strip on the container, by lugs 89 and 90 that will serve to suitably indent the strip, see Fig. 11.

As the containers advance they are suitably ejected onto a transverse belt 91, carried by pulley 92 on a shaft 93, which latter is driven from cross shaft 34 by gears 94, 95. A slide 96 serves to move the container from the conveyer holders onto the belt 91, which slide is operated by a cam 97 and bar 98, that engages a rock lever 99, connected with slide 96 by a link 100.

What I claim is:

1. In a machine for sealing containers, the combination with a table and a conveyer intermittently advanced to successively present the containers at a station, of a carrier arranged above the containers at the station and which is movable to be brought down for engagement with a container on the conveyer, means on the carrier for collapsing and sealing the container, a hopper on the carrier for a superposed pile of angle strips, means on the carrier for feeding one of said strips onto the collapsed container, said means on the carrier thereupon closing said angular strip on the container, said means being operatively connected with the advancing means for the conveyer, whereby the carrier will be brought down on to a container during the rest period of the conveyer, the collapsing and sealing means then actuated, the closure strip then applied, the strip sealing means then actuated, and the carrier with said mechanism thereupon retracted to permit further advance of the conveyer to position another container for cooperation with the said carrier mechanisms.

2. In a machine for sealing containers, the combination with a table and a conveyer intermittently advanced to successively present the containers at a station, of a carrier arranged above the containers at the station and which is movable to be brought down for engagement with a container on the conveyer, jaw means on the carrier for collapsing the container, a hopper on the carrier for feeding one of said strips onto the collapsed containers, jaw means on the carrier for thereupon closing said angular strip on the container, said means being operatively connected with the advancing means for the conveyer, whereby the carrier will be brought down on to a container during the rest period of the conveyer, the collapsing jaws then actuated, the closure strip then applied, the

strip sealing jaws then actuated, and the carrier with said mechanism thereupon retracted to permit further advance of the conveyer to position another container for cooperation with the said carrier mechanisms.

3. In a machine for sealing containers, the combination with a table and a conveyer intermittently advanced to successively present the containers at a station of a carrier arranged above the containers at the station and which is movable to be brought down for engagement with a container on the conveyer, means on the carrier for collapsing and sealing the container, a hopper on the carrier for a superposed pile of angle strips, a feed slide on the hopper to feed a strip onto the collapsed edge of the container, means for actuating said feed means, said means on said carrier being thereupon actuated to secure the said strip, all said means being operatively connected with the advancing means for the conveyer whereby the carrier will be brought down on to a container during the rest period of the conveyer, the collapsing means then actuated, the closure strip then applied, the strip thereupon sealed by said means, and the carrier with said mechanism thereupon retracted to permit further advance of the conveyer to position another container for cooperation with the said carrier mechanisms.

4. In a machine for sealing containers, the combination with means for presenting a container at a certain station, of closure means at said station comprising a pair of sides, a jaw pivoted on each slide, a spring for causing each jaw to project inwardly to engage and collapse a container by the free ends at a place below the top of the container lips when collapsed, said slides as further advanced causing the jaws after engagement with the container to swing and engage a sealing strip by the inner faces of the jaws beyond the said end portion and thereby close the strip on the container lips.

5. In a machine for sealing containers, the combination with means for presenting a container at a certain station, of closure means at said station comprising a pair of slides, a jaw pivoted on each slide, springs for causing the jaws to project inwardly to engage and collapse a container by its free end at a place below the top of the container lips when collapsed, means for thereupon feeding an angular strip onto the closed lips between said jaws, said slides as further advanced causing the jaws after engagement with the container to swing and engage a sealing strip by the inner faces of the jaws beyond the engaged end portion and thereby close the strip on the container lips.

6. In a machine for sealing containers, the combination with means for presenting a container at a certain station, of jaw means at said station comprising a pair of slides,

a jaw movably mounted on each slide, to project inwardly to engage and collapse a container at a place below the top of the container lips when collapsed, said slides as further advanced causing the jaws after engagement with the container to engage a sealing strip beyond the said engaged portion and thereby close the strip on the container lips.

7. In a machine for sealing containers, the combination with means for presenting a container at a certain station, of a pair of closing members at the station, means connected with said members to cause them to be lowered and to advance to engage and collapse the container, said closing members upon further advance being caused to engage the container above the said engaged part by another part of the same members, whereby the closure strip will be sealed.

Signed at New York city, N. Y., on March 19th, 1926.
